UNITED STATES PATENT OFFICE.

STANLEY FIRBAS, OF CHICAGO, ILLINOIS.

DESIGN FOR A COMBINED CIGAR-CUTTER, KNIFE, AND BOTTLE-OPENER.

50,095.

Specification for Design.

Patented Dec. 26, 1916.

Application filed October 14, 1916. Serial No. 125,747. Term of patent 3½ years.

To all whom it may concern:

Be it known that I, STANLEY FIRBAS, a citizen of the United States, residing at Chicago, in the county of Cook and State of Illinois, have invented a new, original, and ornamental Design for a Combined Cigar-Cutter, Knife, and Bottle-Opener, of which the following is a specification, reference being had to the accompanying drawing, forming part thereof.

Figure 1 illustrates a side elevation of a combined cigar cutter, knife, and bottle opener showing my new design. Fig. 2 is a view looking at Fig. 1 in direction of 2—2.

I claim:

The ornamental design for a combined cigar cutter, knife, and bottle opener, as shown.

In witness whereof, I have hereunto subscribed my name this 11th day of October, 1916.

STANLEY FIRBAS.
